UNITED STATES PATENT OFFICE.

THOMAS D. MILLER, OF CLARKSVILLE, MARYLAND.

SHINGLE.

Application filed May 24, 1924. Serial No. 715,644.

To all whom it may concern:

Be it known that I, THOMAS D. MILLER, a citizen of the United States, residing at Clarksville, in the county of Howard and 5 State of Maryland, have invented certain new and useful Improvements in Shingles, of which the following is a specification.

One purpose of this invention is to provide a sheet metal tile or shingle of such 10 form that, in covering a roof, there will be a minimum amount of overlap between the shingles and consequently a minimum amount of metal used; a further object of 15 the invention is to provide a shingle which can be laid quickly and with a minimum amount of labor, and a further object of the invention is to provide a metal shingle having the advantages stated and of such 20 form that the finished roof will be architecturally pleasing.

In the accompanying drawing,

Fig. 1 is a plan view of a part of a roof covering composed of the shingles of my 25 invention;

Fig. 2 is a top perspective view of one of the shingles;

Fig. 3 is a perspective view of the under- 30 side of the shingle;

Fig. 4 is a section on the line 4—4 of Fig. 2;

Fig. 5 is a section on the line 5—5 of Fig. 2;

Fig. 6 is a perspective view of portions 35 of two shingles illustrating the manner of assembling on a roof;

Fig. 7 is a similar view, showing three shingles assembled;

Fig. 8 is a similar view, showing four shingles assembled;

Fig. 9 is a plan view of a part of a roof covering composed of shingles similar to those illustrated in the previous figures but each shingle having a rib on one part; and,

Fig. 10 is a section on the line 10—10 of Fig. 9.

Referring to Figs. 1 to 7, inclusive, of the drawing, A indicates a roof covering composed of a plurality of shingles α , each of the form shown in Figs. 2 to 5, inclusive.

The shingle α is formed from a substantially square piece of sheet metal having the marginal portions of two of its adjacent edges turned backwardly over the top of the sheet, forming flanges 1, and having the

marginal portions of the other two adjacent edges of the sheet turned backwardly under the sheet, forming the flanges 2. The part 3 of the sheet, which may be considered the upper half, is off-set from the part 4, which may be considered the lower half, along a diagonal line extending from the corner 5 to the corner 6 of the sheet, the off-setting portion being indicated at 7. The corner portion 8 of the upper half 3 of the sheet is raised above the body of said half by an off-setting portion 9 which extends parallel with the off-setting portion 7 of the sheet, and a hole 10, for receiving a shingle nail, is punched through the flanges 1 at the apex of this corner portion. The corner portion 11 of the lower half 4 of the sheet is depressed below the plane of the body of the lower half by an off-setting portion 12, which extends parallel with the off-setting portions 7 and 9. The end or apex 11^a of the corner portion 11 is turned backwardly under said corner portion, as shown. The flanges 1 taper from the corner portion 8 toward the off-setting ridge 7, and the flanges 2 taper from the corner portion 11 toward said off-setting ridge.

In assembling the shingles to form a roof covering, the lower halves 4 of a number of shingles are cut off adjacent the line of the off-setting ridges 7, and the upper halves 3 are arranged side by side with the ridges 7 extending along the lower edge of the roof and with the flanges 1 uppermost. These half shingles are secured by nails driven through the perforations 10, and they are also nailed or otherwise secured along their lower edges to the roof. When a row α' of the half shingles has been laid, as indicated in Fig. 1, shingles indicated at α^2 in said figure are applied by sliding each shingle upward over the faces of two adjacent half shingles until the flanges 2 on the shingle which is being applied pass beneath the flanges 1 on the adjacent half shingles and the off-setting ridges 12 are in line with the ridges 7. Each shingle as it is applied is secured to the roof by a nail passed through the opening 10. The next row α^3 of shingles is applied in the same manner by sliding these shingles upward over the adjacent shingle α^2 until the flanges 2 on the shingles α^3 are engaged with the flanges 1 on the shingles α^2 and the off-setting ridges 12 on

the shingles a^3 are in line with the off-setting ridges 7 on the shingles a^2 . In applying the shingles, the inwardly turned lower end 11^a of each shingle slides upon the part 5 of the shingle immediately below it and the converging edges of the shingles at the sides of said lower shingle guide the end 11^a to the upper apex of said lower shingle. The undeturned end 11^a of each shingle 10 thus serves as a means for positioning the lower end of the shingle.

The manner in which the shingles fit together is illustrated in Figs. 6, 7 and 8. In Fig. 6, the flange 2 of an upper shingle a^2 15 is shown in engagement with the flange 1 of the lower shingle a' and the off-setting ridge 9 of the latter shingle is shown in substantial alinement with the off-setting ridge 7 of the upper shingle. In Fig. 7, two upper 20 shingles a^2 are shown, each having a flange 2 engaging the flanges 1 of the lower shingle a' , and the off-setting portions 7 of the upper shingle are in alinement with one another. In Fig. 8, the shingle a' and two 25 shingles a^2 are shown as in Fig. 7 and a fourth shingle a^3 is shown having its flanges 2 engaging the flanges 1 of both shingles a^2 . The inwardly turned end 11^a of the shingle a^3 fits between the converging edges of the 30 lower parts and the off-setting portion 12 of the shingle a^3 is in alinement with the off-setting portions 7 of the shingles a^2 .

As previously stated, the flanges 1 and 2 of each shingle taper toward the diagonal 35 off-setting ridge 7. When a flange 2 of one shingle is interlocked with a flange 1 of another shingle, the narrower end of the flange 2 will fit under the broad end of the flange 1, and the broad end of the flange 2 will 40 fit under the narrow end of the flange 1. Thus, the edge of the flange 2 will engage the bottom of the fold 1^a (Fig. 8), formed by the flange 1, only at one end, and similarly, the edge of the flange 1 will engage the fold 2^a only at one end of said 45 flange. Thus, throughout the greater part of the lengths of the interlocking flanges, the edges of the flanges on one shingle will be spaced from the bottoms of the folds formed 50 by the flanges on the other shingles, and this spacing prevents water from being held within the flanges by capillary attraction.

In finishing the roof covering at the top, it will be apparent that the lower halves 45 of the shingles which were cut off to start the covering at the lower edge of the roof may be used to fill in triangular gaps between the adjacent shingles at the top of the roof. Similarly, in finishing the ends of the 50 roof covering, the shingles may be split vertically, and the parts cut off at one end may be used to fill the gaps between the shingles at the other end of the roof.

It will be noted that the roof covering 55 shown in Fig. 1 is free from alined seams

or ridges running upwardly and downwardly on the roof, which lines and seams are undesirable from an architectural standpoint; it will also be noted that the off-setting ridges in the shingles are in horizontal 75 alinement on the roof, which is desirable from an architectural standpoint. The flanges, as well as the off set ridges on the shingles, prevent water from being driven under the shingles and entering the building. 75

In Fig. 9, the roof is the same as that illustrated in Fig. 1 except that the upper half of each shingle has a rib 13 which extends from the upper apex of the shingle to the transverse off-setting ridge 7. This rib 7 is formed by slightly stretching the metal and it serves the purpose of making the upper part of the shingle more rigid; but its principal function is to give an architectural effect to the roof. It is to be noted that as the ribs are formed only in the upper halves of the shingles, they become staggered on the roof and do not extend in continuous lines, which latter arrangement 90 would be objectionable. The same staggered effect can be obtained by forming the ribs on the lower instead of the upper halves of the shingles, but the arrangement shown is preferred. 95

With both forms of shingle, the edges of the shingles when assembled on a roof run diagonally of the roof, but not in continuous lines; the edges of the shingles in successive rows being offset or out of line with one another, which adds to the architectural effect. 100

It is to be noted that the nail hole 10 in each shingle is punched through the flanges as well as the body of the shingle, so that the nails pass through three thicknesses of the metal and hold the shingle firmly on the roof. As each shingle is fastened to the roof at one point only, and not rigidly secured to the adjacent shingles, the shingles 110 may expand and contract freely with changes in temperature. 110

What I claim is:

1. A shingle comprising a substantially square plate having upper and lower triangular halves offset from one another along a diagonal line, the upper half having its side edges doubled over the top of the plate and the lower half having its side edges doubled under the plate, and the upper and lower corner portions of the plate being oppositely offset on lines parallel with said diagonal line, the upper corner portion being raised and the lower corner portion being depressed with respect to the adjacent portions of the plate. 115

2. A shingle comprising a substantially square plate having upper and lower triangular halves offset from one another along a diagonal line, the upper half hav- 120 125 130

- ing its side edges doubled over the top of the plate and the lower half having its side edges doubled under the plate, said flanges tapering from the upper and lower corners 5 of the plate toward the diagonal line, and the upper and lower corner portions of the plate being oppositely offset on lines parallel with said diagonal line, the upper corner portion being raised and the lower corner portion being depressed with respect to the adjacent portions of the plate.
3. A shingle comprising a substantially square plate having upper and lower triangular halves offset from one another along a diagonal line, the upper half having its side edges doubled over the top of the plate and the lower half having its side edges doubled under the plate, and the upper and lower corner portions of the plate being oppositely offset on lines parallel with said diagonal line, the upper portion being raised and the lower corner portion being depressed with respect to the adjacent portions of the plate and the lower corner being doubled under the plate.
4. A shingle comprising a substantially square plate having upper and lower triangular halves offset from one another along a diagonal line, the upper half having a rib 30 extending from said line to its upper corner and having its side edges doubled over the top of the plate and the lower half having a plane surface and having its side edges doubled under the plate, and the upper and lower corner portions of the plate being oppositely offset on lines parallel with said diagonal line, the upper corner portion being raised and the lower corner portion
- being depressed with respect to the adjacent portions of the plate.
5. A shingle comprising a substantially square plate having upper and lower triangular halves offset from one another along a diagonal line, one half having a plane surface and having a rib extending at 45 a right angle to said line to one of its corners and having its side edges doubled over the top of the plate and the lower half having its side edges doubled under the plate, and the upper and lower corner portions of the plate being oppositely offset on lines parallel with said diagonal line, the upper corner portion being raised and the lower corner portion being depressed with respect to the adjacent portions of the plate.
6. A shingle comprising a substantially square plate having upper and lower triangular halves offset from one another along a diagonal line, and the upper and lower corner portions of the plate being oppositely offset on lines parallel with said diagonal line, the upper corner portion being raised and the lower corner portion being depressed with respect to the adjacent portions of the plate.
7. A shingle comprising a substantially square plate having upper and lower triangular halves offset from one another along a diagonal line and the lower corner portion of the lower half being downwardly offset along a line parallel with said diagonal line.

In testimony whereof I hereunto affix my signature.

THOMAS D. MILLER.
